UNITED STATES PATENT OFFICE

CARL G. OLSON, OF CHICAGO, ILLINOIS, ASSIGNOR TO SHAKEPROOF LOCK WASHER COMPANY, OF CHICAGO, ILLINOIS, A CORPORATION OF DELAWARE

MACHINE FOR FORMING LOCK WASHERS

Application filed May 11, 1928. Serial No. 276,923.

My invention relates to apparatus for producing lock washers and particularly to machines for producing lock washers from flat stock in which one of the margins thereof is 5 serrated.

In the copending applications of R. T. Hosking, Serial Nos. 240,392, 240,393 and 240,394, filed Dec. 16, 1927, methods of producing lock washers from strips of serrated 10 flat stock are described and in general one of the primary objects of my invention is to provide a durable and efficiently operable machine whereby methods set forth in these copending applications may be effectively 15 practiced.

More specifically, an object of my invention is to provide an apparatus whereby flat stock formed with a serrated edge may be fed from a supply thereof and formed into 20 a coil, means being provided for severing a single convolution of the coil thus formed.

Another object of my invention is to provide a machine for coiling strip material and for severing a convolution of the coil thus 25 formed, said machine being further adapted to straighten the helicoidal form of the severed convolution, thereby presenting a flat type washer.

A further object of my invention is to provide an apparatus for coiling a stock strip which varies in thickness into helicoidal convolutions of uniform circular configuration and then severing individual convolutions of 30 the coil to present lock washers of desired shape.

My invention further contemplates the provision of a machine for producing lock washers in which a stock strip is intermittently advanced and formed into a coil, means being provided for controlling the 40 feeding of the strip so that an amount equal to the stock required for one complete convolution of the coil is advanced during each intermittent movement of the feeding means, and a cutting mechanism is provided for severing a convolution upon the completion of each intermittent advancement of the strip.

In addition to the above mentioned characteristics, my invention further contem-

plates the provision of a machine for making lock washers having marginal locking teeth in which a strip of serrated material is formed into a coil having more than one complete convolution and a cutting means is provided for severing one complete convolution, the remaining portion of the coil being employed to facilitate the subsequent coiling operation.

Another object of my invention is to provide a machine for making lock washers from stock strip having marginal serrations or teeth, said device being designed to coil the serrated strip and to sever a complete convolution of the formed coil so that the abutting marginal tooth portions thereof will be properly joined so as to present uniform continuity of the marginal serrations or teeth.

With the foregoing and other objects in view, which will appear in the following description, the invention resides in the novel combination and arrangement of parts and in the details of construction hereinafter described and claimed.

In the accompanying drawings,

Figure 1 is a side elevational view of a machine which represents one embodiment of my invention, a portion of the ram of the press being broken away to disclose certain parts otherwise hidden.

Figure 2 is a horizontal sectional view of the apparatus taken along the line 2—2 of Figure 1.

Figure 3 is a fragmentary transverse vertical sectional view of the machine taken substantially along the line 3—3 of Figure 1.

Figure 4 is a detailed horizontal sectional view of the coiling and severing end of the machine taken substantially on the line 4—4 of Figure 1.

Figure 5 is a transverse vertical sectional view taken along the line 5—5 of Figures 1 and 4.

Figure 6 is a similar vertical transverse sectional view taken along the line 6—6 of Figures 1 and 4, certain portions of the cutting mechanism being shown in elevation for the purpose of clearness.

Figure 7 is a detailed transverse vertical sectional view taken substantially along the

line 7—7 of Figures 1 and 4, and it is to be noted that certain portions of the cutting mechanism are shown in elevation in order that a clearer understanding thereof may be obtained.

5 Figure 8 is likewise a transverse vertical sectional view similar to Figure 7 and is taken along the line 8—8 of Figures 1 and 4.

10 Figure 9 is an enlarged fragmentary horizontal sectional view of certain portions of the cutting mechanism taken along the line 9—9 of Figure 1.

15 Figure 10 is a fragmentary detailed sectional view of the coiling die as viewed along the line 10—10 of Figure 9, the strip material being removed therefrom in order to more clearly understand the manner in which said die is shaped.

20 Figure 11 is an enlarged elevational view of the coiling die as shown in Figure 1, the strip material being removed therefrom in order that a clearer understanding of the die structure may be had.

25 Figure 12 is an enlarged sectional view of the coiling die plunger as shown in Figure 4.

Figure 13 is an enlarged sectional view of the coiling die and plunger as viewed in Figure 6.

30 Figure 14 is an enlarged sectional view of the coiling die and plunger as viewed in Figure 7.

35 Figure 15 is an enlarged perspective view of the forming die disclosed in Figure 11, a strip of serrated material being shown at the entrance of said die, and it is to be understood that this figure discloses the interior of the die as it would appear to an observer whose eye is positioned centrally of and in close proximity to said die.

40 Figure 16 is a perspective view of certain portions of the feeding and cutting mechanisms, a strip of material being shown in association therewith and disclosed as having been advanced by the feeding mechanism and formed into a coil, said coil being in readiness to be acted upon by the cutting mechanism.

45 Figure 17 discloses the cutting mechanism in the process of severing one of the convolutions of the coil and straightening said coil so as to present a flat lock washer, the feeding mechanism being moved rearwardly out of engagement with the serrated strip.

50 Figure 18 discloses the feeding mechanism in position to advance the strip, the position of the strip covering member being clearly shown to indicate how said covering member serves to prevent the buckling of the serrated strip during the advancement or feeding thereof, and

55 Figure 19 is a detailed perspective view of a lock washer which is representative of the type capable of being produced by a machine constructed in accordance with the teachings of my invention.

Referring now to the drawings wherein like numerals have been employed to designate similar parts throughout the various figures, it will be observed that a machine embodying features of my invention comprises a machine frame 10, Figures 1 and 2, and horizontally slidably within the frame is a feeding bar 12. The upper edge of the feeding bar 12 is provided with rack teeth 14 which are designed to mesh with companion teeth of a quadrant 16 keyed to a shaft 18. This shaft 18 is rotatably mounted within a suitable bearing 20 and is secured to one extremity of an actuating arm 22, the other end of said arm being secured to the lower extremity of the actuating rod or shaft 24. This shaft 24 is connected at its upper extremity to one of the moving parts (not shown) of a punch press so that during each complete cycle of operation of said press the shaft 24 will experience one complete reciprocation. From the foregoing it will be clear that during each vertical reciprocation of the shaft 24 the feed bar 12 which supports a feed block 26 at its forward end, will experience one complete horizontal reciprocation.

50 This feed block 26 is mounted upon the feed bar 12 by means of suitable pins 28, Figures 16 to 18 inclusive, which extend through angularly disposed slots 30 provided in said block. The lower edge of the block 26 is formed with rack teeth 32 which are designed for engagement with teeth or prongs 34 of similar design formed along the margin of a strip of metallic stock 36. This stock 36 may be fed into the machine from the left end thereof, Figures 1 and 2, a groove or opening 38, Figure 3, being provided in the machine frame 10 to accommodate said stock. To provide an outer guide for the body portion 40 of the stock 36, I mount a guide plate 42, Figure 1, to the side of the machine frame by means of suitable screws 44. In order to clearly understand the operation of the feed block 26, assume that the feed bar 12 has been carried to its retracted or rearmost position to the left of Figures 1 and 2, and that the feed block 26 occupies the position shown in Figure 18. In this position the pins 28 carried by the feed bar will be positioned in the upper extremity of the slots 30 and the teeth 32 of the feed block will be engaged with the teeth 34 of the strip 36. As the feed bar 12 begins to advance in response to the actuation of the shaft 24, the strip 36 which is guided by means of the plate 42 is advanced toward a coiling die which I have indicated generally by the numeral 46, Figures 1 and 11 to 15 inclusive, later to be described.

55 When the guide block 26 is moved to the limit of its forward stroke as shown in Figure 16, a recess 48 formed at one end of the block 26 will receive the inner end of a locking pin 50, Figures 1, 2 and 4. This locking

pin 50 extends through a side plate 52 which serves as a lateral guide for the block 26 and is carried at the extremity of a leaf spring 54 which is secured by means of a screw 56 to the plate 52. As the rearward movement of the feed bar 12 begins, this pin 50 serves to yieldingly prevent the movement of the feed bar 26 until the pins 28 have been carried to the lower extremities of the slots 30. This movement of the pins 28 within the slots causes the teeth 32 of the block to be disengaged from the teeth in the strip 36 and as the rearward movement of the bar is continued the pin 50 will be disengaged so as to permit the free rearward movement of the block 26. When the block 26 is carried to the end of its rearward stroke, the pin 50 will then be received by a slot or recess 58 which is similar to the recess 48 just described. It will thus be apparent that when the bar again starts on its forward movement, the pin 50 will serve to prevent the advancement of the block 26 until the teeth thereof have been carried into engagement with the companion teeth within the strip 36, as shown in Figure 18. In order to prevent the bulging of the portion of the stock which extends between the feed block 26 and the coiling die 46 during the advancement of said stock, I provide a covering plate 60, Figures 16 to 18, inclusive, which is horizontally slidably transversely of the feed block and is normally urged outwardly through the agency of a suitable coil spring 62. Thus, as the feed bar moves rearwardly, this coil spring 62 will cause the plate 60 to be moved outwardly into covering relation with respect to the upper surfaces of the teeth 34. As the feed block is advanced, the forward edge thereof engages the angular front edge of the plate 60, thereby causing said plate to uncover the stock strip 36 in accordance with the advance movement of the feeding block. From the foregoing it will be clear that the actuation of the block 26 serves to intermittently advance the stock strip 36 into association with the coiling die 46.

The structural characteristics of this coiling die 46 will be best understood by referring to Figures 10 to 15 inclusive wherein the internal structure of said die is shown in detail. In an endeavor to clearly set forth the structural characteristics of the coiling die I have shown a view in Figure 15 which, in a sense, is a radial perspective view, that is, it shows the interior of the die as it would appear to an observer whose eye is positioned centrally of the die and in close proximity thereto. Referring to this figure, as well as to the other corresponding figures, it will be seen that the stock strip 36 enters the die 46 at the opening which I have indicated by the numeral 64, this opening 64 forming a part of a continuous helicoidal groove or path formed within said die. In order to understand the action of the die upon the strip 36,

I have indicated various portions of said helicoidal groove or path by means of reference numerals as will hereinafter appear. After the stock strip enters the die at 64 it is coiled upwardly, and when one-half of a complete convolution has been formed, the extremity of the strip will pass through the helicoidal path at the point 66. From this point 66 the strip will cross the path of a reciprocable shearing bar 68 which forms a part of a cutting mechanism indicated generally by the numeral 70 and which is later to be described. This cutting mechanism 70 also includes an arbor or mandrel 72 which extends into and is positioned centrally of the die 46 and which cooperates with the helicoidal path of the die during the coiling operation. After crossing the path of the shearing bar 68, the advancing end of the strip 36 is coiled downwardly and is directed into association with a portion of the helicoidal path indicated by the numeral 74. It will be observed that at this point 74 the strip will have been coiled into one complete convolution and as the advancement of the strip is continued until the extremity thereof reaches a point 76, said strip will have been formed into one and one-half convolutions. The extent of movement of the feed bar 26 is so arranged that a length of strip material which is sufficient to form one complete convolution within the die 46 is advanced during each forward stroke of the bar 26. In other words, during each forward stroke of the feed bar 12 a point on the stock strip starting from the position indicated by the numeral 66 will pass the position or point 74 and will finally come to rest at the point 76 within the helicoidal path of the die.

When the advanced extremity of the strip 36 is positioned at the point 76 in the manner just described, a forward movement will be experienced by the shearing bar 68 which will carry the cutting edge thereof into engagement with the strip within the die at the point 66, Figure 15. At this point in the description it is to be understood that I provide another shearing member or bar 78 which is suitably mounted in a horizontal fixed position as clearly shown in Figs. 9 and 16 to 18 inclusive. This fixed shearing bar 78 forms a part of the coiling die 46 and is so positioned that when one and one-half convolutions have been formed as hereinbefore described, said bar will occupy a position intermediate said convolutions, as clearly shown in Figure 16. As the shearing bar 68 engages the stock strip, the fixed bar 78 cooperates therewith to facilitate the shearing of the strip at the point 66 and as the forward movement of the shearing bar 68 is continued the severed portion of the convolution is carried across the face of the fixed shearing bar 78 and also across the butt end of the strip positioned at the point 76 within the helicoidal path of the coiling die.

By flexing the severed portion of the convolution in this manner I am able to spring the material comprising the convolution sufficiently so that when the shearing bar 68 is retracted, a flat washer is presented. In other words, the helicoidal form to which the strip material is subjected within the die is straightened so that all parts of the body portion 40 will lie in the same plane.

10 Referring now to the cutting mechanism 70 more in detail, it will be observed that the arbor 72 carries a key or pilot 80 and this key is adapted to enter one of the slots between the teeth 34 of the strip 36 when said arbor and the cutting bar 68 supported thereby are moved forwardly. In this manner the proper positioning of the coil within the die is insured, thereby effecting the severing of the strip along a line which bisects the space 15 between the teeth 34. The arbor 72 is formed integral with a block portion 82, Figure 6, and threaded within one extremity of this block is a pin 84 which carries a coil spring 86. This coil spring 86 is interposed between the side of the machine frame and the head of the pin 84 thereby constantly urging the block 82 to the right, Figure 6. The block 82 is mounted within a sleeve 88 which is longitudinally slidable within a transverse 20 way 90 and reciprocation is imparted to the sleeve 88 through the agency of a vertically slidable member 92, Figures 1, 2 and 8. This member 92 is provided with an angular keyway 94, Figure 8, which is adapted to slidably receive a companion angularly related key 96, Figure 7, provided upon the sleeve 88. The upper end of the member 92 supports a threaded connecting rod 98, Figure 1, which passes through a collar 100 secured 25 to the ram 102 of the punch press and when reciprocation is imparted to the member 92 in response to the actuation of the ram 102, it will be apparent that horizontal reciprocation will be imparted to the sleeve 88. It 30 will be observed that the upper and lower portions of the effective strokes of the ram 102 are employed to actuate the member 92.

Assume that the sleeve 88 occupies the position shown in Figure 6 and that the member 92 is about to experience a downward movement. This will obviously result in a forward movement of the sleeve 88 and when the sleeve has been moved through a predetermined distance a pawl 104, Figure 6, which is normally depressed by means of a leaf spring 106 will be moved into engagement with a stop screw 108, thereby causing the pawl to be urged upwardly against the spring 106 and out of engagement with the block 82. At this point the coil spring 86 causes the sudden retraction of the block 82 and consequently the arbor 72, and as the member 92 is moved upwardly again in response to the upward movement of the press ram 102, the slide 88 will be moved to the

right, Figure 6, and the pawl 104 will again be carried into engagement with the block 82 in readiness for another forward stroke. The quick return of the arbor 72 enables the feed block 26 to advance a subsequent portion of the strip 36 into the coiling die in the manner hereinbefore described.

In the operation of the apparatus just described, the strip material 36 may be fed from a coiled supply thereof (not shown) and directed into proper association with the feed block 26. In response to the vertical reciprocation of the shaft 24 the stock 36 will be intermittently advanced into association with the die 46 in response to the horizontal reciprocation imparted to the feed block. As already described, this die 46 is adapted to form the stock into a coil having one and one-half convolutions and immediately following the coiling of said strip, the shearing bar 68 and the arbor 72 are advanced. The bar 68 is moved forwardly an amount which is sufficient not only to cut the metal strip but also to straighten it and in order to straighten the washer it is necessary to bend the free ends past each other an amount equal to the spring in the material so that when the washer is released and the elasticity of the metal is normalized it becomes a flat ring. As the shear bar 68 reaches its forward limit, the pawl 104 is released and the coil spring 86 operates to quickly retract the shear bar and the arbor so as to permit the introduction of a subsequent portion of the strip into the die 46. When the convolution has been severed and straightened in the manner described, it will fall from the die by reason of its own weight into a suitable receptacle (not shown) provided therefor. In order to positively retain the severed convolution in position within the die until the straightening operation has been completed, I provide a pin 110 which is supported by a lever 112 which is adapted to cause the pin 110 to yieldingly engage the portion of the strip positioned at the point 76 of the die. Immediately subsequent to the straightening operation, the pin 110 is moved to the left, Figure 14, out of engagement with the washer so as to release the completed washer from the die. The lever 112 which carries the pin 110 is hinged at 114 and is operated through the agency of a cam 116 carried by the feed bar 12, Figures 1 and 2. Immediately subsequent to the completion of the coiling operation, the cam 116 engages the free end of the lever 112 so as to carry the pin 110 which is resiliently mounted by means of a suitable coil spring 118 into engagement with the coiled strip at the point 76. The pin 110 thus serves as a means for positively securing the convolution in proper position during the severing and straightening operation. It will also be observed that the teeth 34 of the strip material are twisted out of the plane of the body portion 40 there-

of as clearly shown in dot and dash lines in Figure 13 and thus my improved apparatus is adapted to coil stock strip into helicoidal convolutions of a uniform circular configuration, even though the sections of the stock vary in width when the twisted arrangement of the prong is considered. Although the particular type of apparatus which I have described is designed to produce washers having butt joints, it will be readily understood that washers might be produced which have other types of joints without departing from the spirit and scope of my invention.

From the foregoing it will be understood that my invention contemplates the provision of an apparatus for forming lock washers which is simple in construction and very efficient in operation. By use of my improved device the speed with which lock washers of the prong type may be produced has been greatly accelerated and the type of washers which it is capable of producing meet all the necessary requirements as to uniformity of construction.

Having thus described my invention, what I claim as new and desire to secure by Letters Patent is:

1. In a machine for forming lock washers, means for coiling a strip of material formed with spaced marginal prongs, intermittently operable feeding means adapted to interlock with the marginal prongs in advancing the strip material to the coiling means, and means for severing a single convolution so as to present a lock washer having marginal prongs.

2. In a machine for forming lock washers, means for coiling a strip of material having marginal prongs, intermittently operable means for feeding a predetermined length of the material to the coiling means, said feeding means designed to interlockingly engage the marginal prongs of the strip material, means for severing a single convolution of the formed coil, and means for straightening the helicoidal form of the severed convolution, thereby presenting a flat type washer.

3. In a machine of the class described for forming lock washers, a coiling device including a helicoidal way for receiving strip material formed with marginal prongs and for forming said material into a coil having more than one convolution, means for advancing a length of strip material to the coiling means which is equal to the length of stock required for one complete convolution, and means for severing one convolution so as to present a lock washer having marginal prongs, the portion of the coil remaining in the helicoidal way after the severing of said convolution serving to facilitate subsequent coiling of the material within said way.

4. In a machine for forming lock washers, a coiling means including a helicoidal way for receiving strip material and forming said material into a coil having more than one

complete convolution, a shearing member adapted to sever one complete convolution from a coil formed within the helicoidal way, and a second shearing member associated with the helicoidal way in a position between adjacent portions of the strip convolutions formed therein, said second shearing member co-operating with the first mentioned shearing member to effect the severing of a complete convolution.

5. A machine for forming lock washers from a continuous strip of serrated material including a frame, a feeding mechanism carried by the frame including a reciprocable member having rack teeth formed along the lower edge thereof for engaging with the serrations of the strip material, a strip coiling mechanism provided with a helicoidal way for receiving said strip material, means for disengaging the teeth of the reciprocable member upon the completion of the forward stroke thereof and for actuating the engagement thereof upon the completion of the rearward stroke, and means for severing a convolution of the strip material formed by the coiling means, the operation of said severing means being in timed relation with the actuation of the reciprocable feeding member.

6. In a machine for forming lock washers from strip material having marginal prongs, a material coiling device, reciprocatory means for feeding material to the coiling means, a material guiding means slidable transversely of the material in accordance with the actuation of the feeding means, a reciprocatory mandrel constructed and arranged to cooperate with the coiling device, a reciprocatory pilot member adapted for insertion between adjacent prongs of the strip when said strip is positioned within the coiling means, a pair of cooperative cutting members for severing a convolution of the strip material formed by the coiling device, means for flattening a severed convolution, and a clamping device for securing the convolution in proper position during the severing and flattening operation.

7. In a machine for forming lock washers, means for coiling strip material, means for feeding strip material to said coiling means, and means for severing a convolution of the coil formed within the coiling means, said means including a shearing element movable axially with respect to the coil, and another cooperative shearing element positioned between adjacent convolutions of the coil formed within the coiling means.

8. In a machine for forming a lock washer, a coiling means including a helicoidal way for receiving strip material having spaced marginal prongs, a mandrel centrally positioned with respect to said helicoidal way, a pilot cooperating with said mandrel and insertable between adjacent prongs of the strip material when said strip is positioned within

the coiling means, and means for severing a formed convolution.

9. In a machine for forming lock washers, a coiling means including a helicoidal way for receiving strip material, a reciprocatory mandrel movable axially with respect to said helicoidal way, means for severing a formed convolution, means for frictionally engaging said convolution during the severing thereof, and means for controlling the movement of said coil engaging means in timed relation with respect to the position of the mandrel.

In witness whereof, I have hereunto subscribed my name.

15 CARL G. OLSON.
